UNITED STATES PATENT OFFICE.

CLINTON R. HANNA, OF WILKINSBURG, PENNSYLVANIA, ASSIGNOR TO WESTINGHOUSE ELECTRIC & MANUFACTURING COMPANY, A CORPORATION OF PENNSYLVANIA.

TELEPHONE RECEIVER.

Application filed March 29, 1924. Serial No. 702,746.

My invention relates to telephone receiver devices and more particularly to telephone receiver devices having means for avoiding magnetic saturation of the diaphragm thereof.

One object of my invention is to produce a telephone receiver device in which the magnetic flux produced by the fluctuating current, which is to be translated into sound waves follows a different path through the device than the path traversed by the permanent magnet polarizing flux.

Another object of my invention is to produce a telephone receiver device having magnetic poles symmetrically disposed with respect to the diaphragm.

Another object of my invention is to produce a telephone receiver device in which the variable flux produced by the fluctuating current is passed through a path other than the permanent magnet material.

Another object of my invention is to produce a telephone receiver device in which the variable magnetic flux passes through the diaphragm in a direction parallel to the plane thereof and in which constant flux passes through the diaphragm in a direction at right angles to the plane thereof.

In the prior art of the construction of telephone receivers, it has been customary to provide a permanent magnet, frequently of a U-shaped, with electromagnet windings upon the poles thereof, which poles were placed near to the surfaces of a ferrous material diaphragm. This construction causes the permanent magnetic flux to pass through the material of the diaphragm substantially parallel to the plane thereof from pole to pole of the permanent magnet. The varying flux produced by varying currents in the electromagnet coils is then superimposed upon this steady permanent flux. In consequence, the total flux of the permanent magnet was limited to a value substantially below that which would produce magnetic saturation in material of the diaphragm, since, if the diaphragm was magnetically saturated, a change in flux did not produce a proportionate change in pull upon the diaphragm.

Furthermore, the construction caused the path of the varying flux to be completed through the material of the permanent magnet. It has been found that most perma-

nent magnet steels, especially those having the higher coercive force values, have a low incremental permeability. In consequence, of this fact, a less change in magnetic flux was produced by the fluctuating current than would have been produced had the magnetic circuit been composed entirely of soft iron.

My invention produces a structure in which the flux of the permanent magnet is passed through the diaphragm at right angles thereto and small spots only of the diaphragm are subject to magnetic saturation when powerful permanent magnets are used. My invention further allows the variable flux to pass through the diaphragm in a direction substantially parallel to the plane thereof, whereby the minimum magnetic reluctance is afforded to the variable flux. My construction further provides means whereby the variable flux is conveyed through a magnetic circuit other than the body of the permanent magnet, thereby avoiding the lower value of variable flux which would result from the low incremental permeability of the high coercive force steels.

By this means, I am able to produce a telephone receiver device having a ferrous material diaphragm acted upon directly by the varying magnetic flux produced by the fluctuating electric current, in which a much greater amount of energy may be translated into sound waves, in which a smaller loss of magnetic pull occurs due to the low incremental permeability, and in which permanent magnet steels of much higher coercive force can be used.

Other objects, and structural details of my invention will be apparent from the following description when read in connection with the accompanying drawing in which

Figure 1 is a skeleton plan view of the elements of my invention,

Fig. 2 is a view in vertical section of the elements of my invention,

Fig. 3 is a view in vertical section of an embodiment of my invention taken across the line of the electromagnet coils, and

Fig. 4 is a similar view taken at right angles to the plane of the section in Fig. 3.

Referring to Fig. 1 and Fig. 2, an annular permanent magnet 1 may be made of

steel having a suitable high coercive force. Within the permanent magnet 1 is placed the diaphragm 2. The permanent magnet 1 is magnetized in such a way as to have a north pole at one point on its periphery and a south pole at a point diametrically opposite. Pole pieces 3, 4, 5 and 6 are attached to the permanent magnet 1 at the points of location of these magnetic poles. Pole pieces 10 3 and 4 are attached to the upper surface of the permanent magnet 1 and pole pieces 5 and 6 are attached to the lower surface thereof. Pole pieces 4 and 6 are held together and a low reluctance magnetic path established between them by a clamping piece 7. Pole pieces 3 and 5 are likewise held together by a clamping piece 8. Pole pieces 3, 4, 5 and 6 carry thereon the windings 11, 12, 13 and 14 respectively.

20 Referring to Figs. 3 and 4, a structural embodiment of my invention illustrated therein, comprises the structure illustrated in Figs. 1 and 2. The diaphragm 2 is held in place by magnetic material clamps 7 and 8, and also by clamps 15 and 16 as shown in Fig. 3. A sound channel is formed by a conical piece 17 and its extension 18. Holes are provided in the conical piece 17, which is of non-magnetic material, for the 25 passage of pole pieces 3 and 4. A containing case is also provided consisting of an upper section 19 and a lower section 20. A horn 21, which is attached to the upper section 19, may be replaced by any suitable 30 sound-conveying means.

In the operation of my device, the permanent flux of the magnet 1 is conveyed from the north pole to the south pole thereof through two parallel paths. One of these 40 paths consists of pole piece 6, an air gap 23, a spot upon diaphragm 2, an air gap 24, and pole piece 3. The other path consists of pole piece 4, an air gap 25, a second spot upon the diaphragm, an air gap 26 and pole 45 piece 5.

The windings 11, 12, 13, and 14 are so connected that, when an electric current is passed through them, two separate streams of magnetic flux are formed. One stream 50 flows through a path consisting of pole piece 4, an air gap 25, diaphragm 2, an air gap 23, pole piece 6, and magnetic shunt 7. The other magnetic circuit consists of pole piece 5, an air gap 26, diaphragm 2, an air gap 55 24, pole piece 3, and magnetic shunt 8. The connections of coils 11, 12, 13 and 14 are such that the magnetic flux produced in the two paths tends to flow in the same direction through the material of diaphragm 2.

60 The permanent magnet flux, or constant flux, thus passes through the diaphragm 2 only at spots between pole pieces 3 and 6 and pole pieces 4 and 5, only a small amount of leakage flux passing through other portions of diaphragm 2. The varying flux

produced by coils 11, 12, 13 and 14 likewise passes into the same small spots in the diaphragm, but it does not pass directly through. Instead, it is conveyed by the body of the diaphragm 2 from pole piece 4 70 to pole piece 3 and from pole piece 5 to pole piece 6. By this means, the body of the diaphragm 2 is kept relatively free from the steady flux and is left available for a maximum value of varying flux. It is therefore, 75 possible to act upon the diaphragm 2 by a much higher value of varying fluxes without approaching magnetic saturation of the diaphragm material than is possible by the construction common in the prior art. 80

This construction produces one in which two paths are available for the varying flux having a portion of their paths in common. The common portion is the diaphragm. Such a disposition is called a "figure eight" 85 distribution.

Furthermore, the fact that the magnetic path of the varying flux induced in pole pieces 3 and 5 by coils 11 and 13, is conveyed by magnetic shunt 8 rather than by the body 90 of permanent magnet 1, and that the flux induced in pole pieces 4 and 6 by coils 12 and 14 is conveyed through the magnetic shunt 7 rather than the body of permanent magnet 1, avoids the influence of the low incremental 95 permeability of permanent magnet 1 upon changes in the varying fluxes. By this means, it is possible to use a magnetic material having a low incremental permeability which is usually concomitant with high coercive force, without the losses which would otherwise occur because of such low incremental permeability. 100

By this means, I have produced a telephone receiver device which is capable of 105 handling larger energy input than devices of the prior arts and which avoids many of the losses incident to construction of the prior art.

While I have shown but one embodiment 110 of my invention in the accompanying drawings, it is capable of various changes and modifications without departing from the spirit thereof, and it is desired, therefore, that only such limitations shall be imposed 115 thereon as are indicated in the prior art or in the appended claims.

I claim as my invention:

1. A telephone receiver device comprising 120 in combination a diaphragm, a permanent magnet, four electromagnets attached thereto and symmetrically disposed on opposite sides of said diaphragm, and a horn cooperating therewith.

2. A telephone receiver device comprising 125 in combination a diaphragm of magnetic material, a permanent magnet of material having a high coercive force and a low incremental permeability, four electro-magnets having cores of low incremental permeabil- 130

- ity attached thereto and disposed on opposite sides of said diaphragm.
3. A telephone receiver device comprising in combination a diaphragm, a sound channel cooperating therewith, a permanent magnet, four pole pieces attached thereto and disposed on opposite sides of said diaphragm whereby magnetic flux from said magnet is conveyed through said diaphragm substantially at right angles to the plane thereof, a plurality of electromagnetic windings upon said pole pieces adapted to cause a flux to traverse a path between said pole pieces, within said diaphragm, in a direction parallel to the plane thereof.
4. A telephone receiver device comprising in combination, an iron diaphragm, a sound-conveying channel member and a permanent magnet having a high coercive force also operating therewith, four pole pieces having a high magnetic permeability attached to the poles of said permanent magnet, four electromagnet coils respectively mounted on said pole pieces, said pole pieces and coils being symmetrically disposed on opposite sides of said diaphragm, a containing case for protecting said diaphragm, magnets, coils and sound channel, and a horn operatively associated with said diaphragm and said sound channel.
5. A telephone receiver device comprising a diaphragm, an electric circuit, a protecting and supporting case portion and a magnetic circuit having a portion traversed by constant flux and adapted to be energized with a varying flux by said electric circuit, said dia-
- phragm being a portion of said magnetic circuit and being so placed with respect to other portions of said magnetic circuit that part of it is traversed by varying flux only. 40
6. A telephone receiver device comprising a diaphragm and a plurality of cooperating magnetic circuits adapted to be traversed only by constant flux in certain portions thereof, and only by varying flux in certain other portions thereof.
7. A telephone receiver comprising a diaphragm, a source of constant magnetomotive force, a source of varying magnetomotive force and a magnetic circuit for the constant flux traversing certain portions only of said diaphragm, other portions of said diaphragm being traversed by the varying flux.
8. A telephone receiver comprising a diaphragm, means for impressing a constant flux and means for impressing a varying flux upon said diaphragm, the said means directing the two fluxes differently, whereby the paths of the fluxes within the diaphragm are different.
9. In a telephone receiver, a diaphragm, a source of direct magnetomotive force, a magnetic circuit associated therewith and producing two poles of like sign on opposite sides of the diaphragm and two poles of the opposite sign also on opposite sides of the diaphragm, and magnetic shunts each connecting the poles of like sign.
- In testimony whereof, I have hereunto subscribed my name this 24th day of March 1924.

CLINTON R. HANNA.
